CLUTCH MECHANISM

Jasper F. Cullin, Detroit, Mich., assignor to two-thirds to Lou Mervis, Lock Haven, Pa.

Application April 21, 1941, Serial No. 389,583

17 Claims. (Cl. 192—63)

The invention relates to clutch mechanism of the type adapted for use in starters for internal combustion engines.

In starting internal combustion engines, a backfire sometimes occurs and this results in a high torque, opposed to the force applied for driving the engine in the operating direction or the engine may be stuck so that the torque required to start it may be excessive. If the driving member of the starter is engaged by the driving means therefor, a backfire sometimes produces torque which may be destructive of the mechanism of the starter. For example, in starting mechanism which includes eccentric-operated pawls and a ratchet wheel, such as exemplified in my application for patent for Starting mechanism for internal combustion engines, Serial No. 343,762, filed July 3, 1940, issued as Patent No. 2,256,466 on Sept. 23, 1941, the wheel remains engaged by the pawls during a starting operation. If a backfire occurs while the pawls are engaged with the ratchet wheel, the torque from the engine is transmitted to the ratchet wheel and pawls. This torque may result in breakage or render the starter inoperative. It is also desirable to provide in the starter a resilient drive for the crankshaft.

One object of the invention is to provide a clutch mechanism with a maximum torque throw-out so that the driving member thereof will be uncoupled or disengaged from the driven element in the event of a backfire or when the torque required to turn the engine is excessive for any other reason.

Another object of the invention is to provide an improved clutch mechanism which is adapted for engine starters, which includes a maximum torque throw-out and a resilient driving connection between the driving member of the starting mechanism and the driven member.

Another object of the invention is to provide a clutch mechanism of this type which is simple in construction and efficient in operation.

Other objects of the invention will appear from the detailed description.

The invention consists in the several novel features which are hereinafter set forth and are more particularly defined by claims at the conclusion hereof.

In the drawing: Fig. 1 is a view, partly in section and partly in elevation, illustrating a clutch mechanism embodying the invention in its inoperative or normally disengaged position. Fig. 2 is a similar view illustrating the clutch mechanism when the driving member has been auto-

matically released by excess torque. Fig. 3 is a section on line 3—3 of Fig. 1. Fig. 4 is a section taken on line 4—4 of Fig. 2.

The invention is exemplified with the shaft *a* of an internal combustion engine and a case *b* which encloses the clutch mechanism and is usually secured to one end of the engine. The clutch mechanism comprises an outer annular driving member or wheel *6*, which is provided with ratchet teeth *5* and is adapted to be driven to start the engine by a pair of pawls *7* and *8*, which are journaled on oppositely disposed eccentricities *9* and *10* on a shaft *11*. The pawls are each provided with a counterweight *12* for normally holding their operative ends *13* disengaged from the ratchet wheel or member *6*, and are controlled to engage and disengage the ratchet for the operation of the starting mechanism by a pair of resilient arms *14* engaging the pawls *7*, *8*, respectively, and secured to a shaft *15* which is usually manually shiftable by means of a handle. Shaft *11* and eccentricities *9* and *10* may be driven by an electric motor, as exemplified in my application Serial No. 343,762, or by any suitable means, to operate pawls *7* and *8*.

The clutch mechanism also comprises a spider or inner member which includes an annulus *16* which is keyed to the engine shaft *a* and integral outwardly extending arms or lugs *17*; an intermediate member which includes a ring or annulus *18* and integral inwardly extending lugs or abutments *19* adapted to be engaged by the arms *17* of the spider; and coil springs *20* which are loaded, as hereinafter described, and extend between abutments *19* on the intermediate member and the arms *17* of the spider, respectively. Ratchet wheel *6* is in the form of a ring which is supported on, fits around, and is rotatable relatively to, ring *18* of the intermediate member. The outer ends of arms *17* extend to and fit the inner periphery of ring *18* of the intermediate member and support the latter coaxially with the shaft *a*. Annular plates *21* are secured to ring *18* by through-rivets *22* and lap the sides of member *6* to retain said member against endwise movement relatively to ring *18* and arms *17* of the spider fit between plates *21* and secure the latter and ring *18* against endwise movement relatively to shaft *a*.

A pin or locking member *24* is radially and slidably mounted in a radial socket *25* in the intermediate member. The pin *24* is provided at its outer end with a conical portion *26* which fits into a correspondingly tapered socket *27* in the inner face of the driving member *6*. The

pin 24 is provided at its inner end with a tapered portion 23 which fits in, and is adapted to pass into a corresponding tapered conical socket 29 in the outer periphery of annulus 16 of the spider which is keyed to shaft a. The locking pin 24 is adapted, while its outer tapered end 26 is engaged with socket 27 in the driving member 6, to be locked in such engagement by a peripheral portion 16^a of the annulus 16 of the spider. Pin 24 is also adapted to be locked in socket 29 in the annulus 16 of the spider by the inner periphery 6^a of the outer driving member 6. When pin 24 is engaged with socket 27 in driving member 6, the latter will be drivably connected by the pin to the intermediate member and the latter will be adapted to drive the inner member or spider through the springs 20. When pin 24 is engaged with socket 29 in the inner member or spider, it will be disengaged from driving member 6 and permit relative rotation of the driving member 6 and the intermediate member which is then locked to member 16 by the pin. The tapered ends of the pin 24 and the taper of sockets 27 and 29 are adapted to alternately cam the pin from one socket into the other, responsive to torque.

The operation will be as follows: when the starter is not in use, pawls 7 and 8 will be held disengaged from the ratchet teeth on the driving member 6; pin 24 will be in the position illustrated in Fig. 1; and its outer end will be locked in socket 27 of the member 6 by the outer periphery 16^a of annulus 16 of the spider, as shown in full lines in Fig. 1.

To start the engine, the operator will rock arms 14 to press pawls 7 and 8 into engagement with ratchet teeth 5 of wheel 6 and the eccentrics 9 and 10 will be continuously driven to alternately and successively engage teeth 5 and drive the ratchet wheel 6. The springs 20 are loaded for compression a predetermined normal maximum torque, which will start the engine before pin 24 registers with socket 29 in the spider. When the torque required to turn the engine does not exceed said maximum, pin 24 will be held locked to ratchet wheel 6 by peripheral portion 16^a of the spider. When the engine starts, wheel 6 will overrun pawls 7 and 8, and the torque on ratchet wheel 6 from the pawls will be released and springs 20 will rotate the intermediate member and pin 24 until arms 17 on the spider engage abutments 19 on the intermediate member. It is not necessary for the operator to immediately disengage pawls 7 and 8 after the engine has started. If the torque required to turn the engine exceeds the predetermined maximum, or in the event of a backfire which produces an excessive opposed torque from the engine through the spider, springs 20 will be compressed sufficiently to permit pin 24 to register with the socket 29 in the inner member or spider. The tapered engagement between end 26 of pin 24 and socket 27 in the ratchet wheel, when the torque exceeds a predetermined maximum from wheel 6 or from the spider in case of a backfire, will cam the pin radially inward into socket 29 in the spider and out of socket 27 in the ratchet wheel 6. When pin 24 has been cammed out of socket 27, the inner periphery 6^a of wheel 6 will hold pin 24 engaged with the spider and uncoupled from the ratchet wheel, as illustrated in Fig. 2. The drive wheel 6 will then be free to be driven by pawls 7 and 8 for approximately one revolution and wheel 6 rotated to again bring pin 24 into registry

with socket 27 without applying torque to the intermediate member and the spider. If the excessive torque has been eliminated the pressure of springs 20 will cause tapered socket 29 to cam pin 24 outwardly to disengage it from the spider and lock it to wheel 6 for the next starting operation.

The invention exemplifies simple and efficient clutch mechanism which is particularly adapted for use in starters for internal combustion engines in which the outer driving member resiliently drives the engine in starting and is automatically uncoupled from the intermediate member responsive to torque in excess of a predetermined maximum.

The invention is not to be understood as restricted to the details set forth, since these may be modified within the scope of the appended claims, without departing from the spirit and scope of the invention.

Having thus described the invention, what I claim as new and desire to secure by Letters Patent is:

1. Clutch mechanism comprising a wheel, an inner member, an intermediate member, said wheel and members being connected for relative rotation, resilient driving means between said members, a locking element movably mounted on the intermediate member for driving the intermediate member, from the wheel and responsive to torque from the wheel for uncoupling the wheel and intermediate member, and means on the wheel for holding the element uncoupled from the wheel.

2. Clutch mechanism comprising a wheel, an inner member, an intermediate member, said wheel and members being connected for relative rotation, resilient driving means between said members, a locking element movably mounted on the intermediate member for driving the intermediate member from the wheel and responsive to torque from the wheel in one direction for uncoupling the wheel and intermediate member, means on the wheel for holding the element uncoupled from the wheel, and means on the inner member operable by said resilient driving means for shifting the element to couple the wheel and intermediate member.

3. Clutch mechanism comprising a wheel, an inner member, an intermediate member, said wheel and members being connected for relative rotation, resilient driving means between said members, a locking element movably mounted on the intermediate member for driving the intermediate member from the wheel and responsive to torque from the wheel in one direction for uncoupling the wheel and intermediate member, means on the wheel for holding the element uncoupled from the wheel, means on the inner member responsive to said resilient driving means for shifting said element to couple the wheel and the intermediate members, and means on the inner member for holding the element coupled to the wheel.

4. Clutch mechanism comprising a wheel, an inner member, an intermediate member, said wheel and members being connected for relative rotation, resilient driving means between said members, a locking element movably mounted on the intermediate member for driving the intermediate member from the wheel and responsive to torque from the wheel in one direction for uncoupling the wheel and intermediate member, a peripheral surface on the wheel for holding the element uncoupled from the wheel, means on

the inner member responsive to said resilient means for shifting said element to couple the wheel and the intermediate member, and a peripheral surface on the inner member for holding the element coupled to the wheel.

5. Clutch mechanism comprising a wheel, an inner member, an intermediate member, said wheel and members being connected for relative rotation, resilient driving means between said members, a locking pin slidably mounted on the intermediate member for driving the intermediate member from the wheel, means between the wheel and the pin responsive to torque from the wheel for slidably shifting the pin to uncouple the wheel and intermediate member, and means on the wheel for holding the pin uncoupled from the wheel.

6. Clutch mechanism comprising a wheel, an inner member, an intermediate member, said wheel and members being connected for relative rotation, resilient driving means between said members, a locking pin slidably mounted on the intermediate member for driving the intermediate member from the wheel, means between the wheel and the pin responsive to torque from the wheel for slidably shifting the pin to uncouple the wheel and intermediate member, means on the wheel for holding the pin uncoupled from the wheel, and means on the inner member for shifting the pin to couple the wheel and intermediate member.

7. Clutch mechanism comprising a wheel, an inner member, an intermediate member, said wheel and members being connected for relative rotation, resilient driving means between said members, a locking pin slidably mounted on the intermediate member for driving the intermediate member from the wheel, means between the wheel and the pin responsive to torque from the wheel for slidably shifting the pin to uncouple the wheel and intermediate member, means on the wheel for holding the pin uncoupled from the wheel, means on the inner member for shifting the pin to couple the wheel and intermediate member, and means on the inner member for holding the pin coupled to the wheel.

8. Clutch mechanism comprising a wheel, an inner member, an intermediate member, said wheel and members being connected for relative rotation, resilient driving means between said members, a locking pin slidably mounted on the intermediate member for driving the intermediate member from the wheel, means between the wheel and the pin responsive to torque from the wheel for slidably shifting the pin to uncouple the wheel and intermediate member, a peripheral surface on the wheel for holding the pin uncoupled from the wheel, means on the inner member for shifting the pin for drivably coupling the wheel and intermediate member, and a peripheral surface on the inner member for holding the pin coupled to the wheel.

9. Clutch mechanism comprising a wheel, an inner member provided with outwardly extending arms, an intermediate member on which the wheel is rotatably mounted and provided with inwardly extending abutments adapted to be engaged by the arms, resilient driving means between the abutments on the intermediate member and the arms on the inner member, a locking pin slidably mounted in the intermediate member for driving the intermediate member from the wheel, the wheel being provided with a socket to receive the pin, torque-responsive cam means for uncoupling the wheel from the

intermediate member, and means on the inner member for holding the pin coupled to the wheel.

10. Clutch mechanism comprising a wheel, an inner member provided with outwardly extending arms, an intermediate member on which the wheel is rotatably mounted and provided with inwardly extending abutments adapted to be engaged by the arms, resilient driving means between the abutments on the intermediate member and the arms on the inner member, a locking pin slidably mounted in one of the abutments of the intermediate member for coupling and uncoupling the wheel and the intermediate member, the pin being provided with tapered ends, the wheel and inner member being provided with sockets adapted to receive the ends of the pins respectively, said ends and sockets being torque-responsive for uncoupling the wheel from the inner member, means on the inner member for holding the pin coupled to the wheel, and means on the wheel for holding the pin uncoupled therefrom.

11. Clutch mechanism comprising a wheel, an inner member provided with outwardly extending arms, an intermediate member on which the wheel is rotatably mounted and provided with inwardly extending abutments adapted to be engaged by the arms, resilient driving means between the abutments on the intermediate member and the arms on the inner member, a locking pin slidably mounted in one of the abutments of the intermediate member for coupling and uncoupling the wheel and the intermediate member, the pin being provided with tapered ends, the wheel and inner member being provided with sockets adapted to receive the ends of the pins respectively, said ends and socket being torque-responsive for uncoupling the wheel from the inner member, a peripheral surface on the inner member for holding the pin coupled to the wheel, and a peripheral surface on the wheel for holding the pin uncoupled therefrom.

12. In clutch mechanism for an engine starter, the combination of a toothed wheel, means engageable with the teeth for driving the wheel, an engine-rotatable inner member, an intermediate member within the wheel around, and rotatable relatively to, the inner member and to the wheel, a resilient driving connection between the members, a locking element movably mounted in the intermediate member for driving the intermediate member from the wheel and responsive to torque from the wheel while it is being driven and to torque produced by a backfire of the engine, for uncoupling the locking element and the wheel, means on the wheel for holding the pin uncoupled from the wheel, and means on the inner member for holding the element coupled to the wheel.

13. In clutch mechanism for an engine starter, the combination of a toothed wheel, means engageable with the teeth for driving the wheel, an engine-rotatable inner member, an intermediate member within the wheel around, and rotatable relatively to, the inner member and to the wheel, a resilient driving connection between the members, a locking pin slidably mounted in the intermediate member for driving the intermediate member from the wheel and responsive to torque from the wheel and to torque produced by a backfire of the engine for uncoupling the pin and the wheel, means on the wheel for holding the pin uncoupled from the wheel, and means

on the inner member for shifting the pin to couple the wheel and intermediate member.

14. In clutch mechanism for an engine starter, the combination of a toothed wheel, means engageable with the teeth for driving the wheel, an engine-rotatable inner member, an intermediate member within the wheel around, and rotatable relatively to, the inner member and to the wheel, a resilient driving connection between the members, a locking element movably mounted in the intermediate member for driving the intermediate member from the wheel and responsive to torque from the wheel and to torque produced by a backfire of the engine for uncoupling the locking element and the wheel, peripherally extending means on the wheel for holding the pin uncoupled from the wheel, means on the inner member for shifting the element to couple the wheel and intermediate member, and peripheral means on the inner member for holding the element coupled to the wheel.

15. In clutch mechanism for an engine starter, the combination of a toothed wheel, means engageable with the teeth for driving the wheel, an engine-rotatable inner member, an intermediate member within the wheel around, and rotatable relatively to, the inner member and to the wheel, a resilient driving connection between the members, a locking pin slidably mounted in the intermediate member for driving the intermediate member from the wheel and responsive to torque from the wheel and to torque produced by a backfire of the engine for uncoupling the locking pin and the wheel, peripherally extending means on the wheel for holding the pin un-

coupled from the wheel, means on the inner member for coupling the pin to the wheel, and peripheral means on the inner member for holding the pin coupled to the wheel.

16. In clutch mechanism, the combination of a wheel, an inner member, an intermediate member, resilient driving means between the inner and intermediate members, said wheel and members being mounted for relative rotation, a locking pin slidably mounted in the intermediate member and slideable to alternately lock together the intermediate member and the outer member and the inner and intermediate members and torque-responsive for shifting the locking pin to lock the pin to the wheel or the inner member.

17. In clutch mechanism, the combination of an outer annular wheel provided with a socket on its inner periphery, an inner member provided with an annulus and arms and a socket in the outer periphery of the annulus, an intermediate member between the inner and outer members provided with abutments engageable with said arms, a resilient driving connection between the inner member and the intermediate member, a locking element slidably mounted in the intermediate member, the inner and outer ends of the pin and said sockets being tapered to shift the element responsive to predetermined torque, the annulus of the inner member having a peripheral surface for holding said element engaged with the wheel, the wheel having a peripheral surface for retaining the locking element engaged with the socket in the annulus of the inner member.

JASPER F. CULLIN.
